UNITED STATES PATENT OFFICE.

ALF SCOTT-HANSEN, OF CHRISTIANIA, NORWAY, ASSIGNOR TO NORSK HYDRO-ELEKTRISK KVAELSTOFAKTIESELSKAB, OF CHRISTIANIA, NORWAY.

ELECTRIC FURNACE.

1,096,321.

Specification of Letters Patent. Patented May 12, 1914.

Application filed January 6, 1914. Serial No. 810,674.

To all whom it may concern:

Be it known that I, ALF SCOTT-HANSEN, a subject of the King of Norway, residing at Christiania, Norway, have invented certain new and useful Improvements in Electric Furnaces; and I do hereby declare the following to be a full, clear, and exact description of the invention, such as will enable others skilled in the art to which it applies to make and use the same, reference being had to the accompanying drawings; and to letters or figures of reference marked thereon, which form a part of this specification.

15 This invention relates to improvements in the gas-supply in electric arc furnaces.

In electric furnaces operating with magnetically spread disk shaped flames the air (or gases, respectively) as a rule has been introduced at about right angles to the flame disk. I have now found that by conducting the gases in such a manner that the two currents of gas passing from the sides of the furnace inwardly toward the flame disk will, considered as a whole, assume the form more or less of truncated cones having their base in the plane of the flame disk. Various advantages will be obtained, said advantages being partially assisted, if the passages be at the same time so inclined that a rotary motion will be imparted to the gas cones. The output of the furnace will be improved by the fact that the gases may be more easily directed in the proper quantities inwardly toward the various zones of the flame disk, *inter alia* because, with the new manner of supply, disturbances will not so easily occur through whirl motion produced by too sudden change of the direction of motion. Furthermore it is of advantage for the efficiency of the furnace that the gas particles are caused to follow the flame disk with a more readily controllable velocity without the possibility of being thrown back and of partaking in the aforesaid disturbing whirl motions which are detrimental to the reaction action. The direction of motion imparted to the gases will drive the same with greater velocity toward the outlet openings and the cooling. It will also be possible with the new method of conducting the gases to somewhat reduce the magnetization, which is of advantage both with respect to economy and otherwise.

A mode of carrying out the invention is 55 illustrated by way of example in the accompanying drawing which represents a section through the furnace. The arrows indicate the passage of the gases.

a designates annular gas distribution 60 chambers provided for the various zones of the furnace, *b* the outlets for the gases. The object of the chambers *a*, each of which communicate separately with a gas supply pipe, is to enable the air or gas to be distributed 65 at will to the various parts of the furnace. In this manner also gases of different nature, or of different temperatures, may be supplied to the different zones of the furnace. If it is desired to use, in a known manner, 70 previously treated, cooled gases for quickly cooling the reaction gases, the same may be supplied through the outer gas distribution chambers.

As it will be seen from the drawing, the 75 air or gas supply passages *c*, are narrowed inwardly toward the flame chamber. Thereby it is rendered possible not only to use a higher pressure for the gases but a more reliable cooling action will be insured, and also 80 the danger of electrically overcharging the surface of the brickwork will be reduced by the increased velocity of the entering air or gases, respectively.

I claim:

1. In electric furnaces with magnetically spread disk shaped flames, passages for blowing currents of air or gas from the sides of the furnace toward the flame disk into the furnace chamber, said passages being so directed that the currents, considered as a whole, will assume the form of truncated cones having a common base in the plane of the flame disk.

2. In electric furnaces with magnetically 95 spread disk shaped flames, passages for blowing currents of air or gas from the sides of the furnace toward the flame disk, into the furnace chamber, said passages being so directed that the currents, considered as a whole, will assume the form of truncated cones having a common base in the plane of the flame disk and being given such a position that a rotary motion will be imparted to the two currents of air or gas, 100 respectively, blowing against the flame.

3. In electric furnaces with magnetically spread disk shaped flames, passages for

blowing currents of air or gas from the sides of the furnace toward the flame disk, into the furnace chamber, said passages being so directed that the currents, considered as a whole, will assume the form of truncated cones having a common base in the plane of the flame disk, said passages communicating in groups with distribution chambers.

4. In electric furnaces with magnetically spread disk shaped flames, passages for blowing currents of air or gas from the sides of the furnace toward the flame disk, into the furnace chamber, said passages being so directed that the currents, considered as a whole, will assume the form of truncated cones having a common base in the plane of the flame disk and being given such a position that a rotary motion will be imparted to the two currents of air or gas, blowing against the flame, and outer chambers for

supplying cooled reaction gases to the flame chamber.

5. In electric furnaces with magnetically spread disk shaped flames, passages for blowing currents of air or gas from the sides of the furnaces toward the flame disk, into the furnace chamber, said passages being so directed that the currents, considered as a whole, will assume the form of truncated cones having a common base in the plane of the flame disk, said passages being narrowed in a direction toward the flame chamber. 25

In testimony that I claim the foregoing as my invention, I have signed my name in presence of two subscribing witnesses. 30

ALF SCOTT-HANSEN.
